FLOW CONTROL DEVICE

Albert Kingsley, Montreal, Quebec, Canada

Application December 22, 1933, Serial No. 703,521

8 Claims. (CL 226—127)

The present invention relates to a novel flow control device designed especially for use in the filling of tank cars with gasoline or oil, although useful generally in the filling of vessels.

The principal object of the invention is to provide a removable device of this character whereby the flow into the vessel is automatically cut off on attainment of a predetermined liquid level within the vessel. Accordingly, the device comprises a float disposed within the vessel and adapted to operate a valve in the supply line on reaching a predetermined level.

The supply line contains a valve which has a tendency to close under the action of the weight. In filling the vessel, the valve is held open by means counteracting the weight. This means, however, is released by a part of the float structure when the float reaches a given level. The holding means for the valve may be mechanical or electrical. In the former case, it consists preferably of a number of gripping shoes holding a cable which extends from the weighted valve. These shoes are released by the float structure, whereupon the valve is permitted to open under the action of the weight. In the electrical system, the weighted valve is held open by an electromagnet, and the circuit is broken by a member carried by the float when the latter reaches a predetermined level.

The invention is fully disclosed by way of example in the following description and in the accompanying drawing in which:

Figure 1 is a detail longitudinal section of a tank car equipped according to the invention;

Figure 2 is an elevation of the control apparatus partly in section;

Figure 3 is a top plan view;

Figure 4 is a section on the line 4—4 of Fig. 2;

Figure 5 is a detail section of the pulley;

Figure 6 is a detail section partly in elevation at the pulley;

Figure 7 is a detail view of a modified mechanical system; and

Figure 8 is a detail perspective view thereof.

Reference to these views will now be made by use of like characters which are employed to designate corresponding parts throughout.

In Figure 1 is illustrated a portion of a tank car 1 having the usual filling dome 2. The usual man hole cover in the dome is replaced by a removable cover plate 3 from which is suspended a frame or cage consisting mainly of a circular series of vertical strips 4. The frame is completed by a number of cross bars 5 at the lower

ends of the strips and further by several bands 6 surrounding the strips.

A float 7 is adapted to move vertically in the cage and in this connection the inner face of each strip 4 is formed with a longitudinal rib 5 to reduce the friction, as may be seen more clearly in Figure 4. Arms 9 extend upwardly from the float, and are bent inwardly as at 10 at their upper ends which carry a collar 11 for the purpose which will presently appear. The arms are formed with extensible joints 12 for regulating the distance between float 7 and the collar 11.

The bands 6 also support the filling pipe 13 which is adapted for connection to the loading or supply pipe 14 by means of a flexible section 15. The pipe 14 joins the valve 16 which is opened and closed by a movement of the lever 17. The lever 17 carries a weight 18 so positioned that it has a normal tendency to close the valve. 20

A pair of brackets 19 are suspended from the lower surface of the plate 3 and serve to support a rotatable pulley 20 therebetween. A cable 21 extends from the unweighted end of the lever 17 and is wound on the pulley 20 by the action 25 of a coil spring 22 within the pulley as clearly shown in Figure 5. The tension of the spring, however, is not sufficient to raise the weight 18.

To the lower surface of the plate 3 are also pivotally mounted two forked levers 23 at opposite sides of the cable 21. The inner ends of the levers carry friction shoes 24 adapted to engage the cable and hold it against shifting. Springs 25 connect the levers to the plate 3 and normally draw the levers into gripping position. The remaining ends of the levers are respectively forked, and each such end comprises a finger 26 extending over the collar 11 and another finger 27 passing through an aperture 28 in the plate 3. 30

By means of the joints 12, the arms 9 are so adjusted that the collar 11 will engage the fingers 26 when the float 7 reaches a predetermined height, namely, a height representing a level to which the tank is to be filled. When the fingers 26 are thus displaced by contact with the collar 45 11, the shoes 24 are swung out of gripping engagement with the cable 21. The weight 18 is now free to descend and close the valve. If it is desired for any reason to close the valve at an earlier period, the forks may be manually actuated 50 by manual pressure on one or both of the fingers 27 in the direction of the arrows shown in Figure 6.

A tensioned pulley 20 holds the cable taut between the lever 17 and the shoes 24 and further 55

prevents it from accumulating upon the float. The cable is guided to the pulley 20 by means of a ring 29 supported between the brackets 19 as shown in Figures 2 and 6.

- 5 The collar 11 further carries a gauge 30 or level indicator passing through a plate 3 and therefore visible outside the car. The plate further carries a safety valve 31 to permit overflowing in case of overfilling, and also to assist in the displacement of air during filling. The lower end of the pipe 13 is preferably screw threaded as at 32 for the adjustment of another pipe extending to the bottom of the car in order to prevent the formation of gas and bubbles.
- 10 15 Inasmuch as the device is carried by the removable cover plate 3, it is removable therewith and thereby suited for use on tank cars and other rolling stock for carrying liquids.

In Figures 7 and 8 is illustrated another mechanical control system embodying brackets 53 suspended from the lower surface of the plate 3 and supporting rotatably therebetween a pulley 54 and ratchet gears 55 on each side and all three held together. Brackets 53 also support rotatably 25 a double curved lever 56 with a roller 57 at one end and pawls 58 at the other end.

Normally pawls 58 engage ratchet gears 55 and the cable 59 wound on the pulley 54 is prevented from shifting. When the float 60 reaches the 30 predetermined height, roller 57 is pushed upwardly thus disengaging ratchet wheel 55 from pawls 58 and cable 59 is free to let the weight descend and close the valve.

35 A vertical stem 61 engaging a tongue 62 formed in the center of lever 56 may also be used for releasing the cable 59 from the outside.

Although specific embodiments of the invention have been illustrated and described, it will be understood that various alterations of the details 40 of construction may be made without departing from the scope of the invention, as indicated by appended claims.

What I claim is:

- 45 1. A flow control device comprising a frame adapted to be removably mounted in a vessel to be filled, a float guided in said frame, a supply pipe adapted for insertion in said vessel through said frame, a valve in said pipe, a weight normally tending to close said valve, a cable adapted to lift said weight and open said valve, gripping shoes adapted to hold said cable against the action of said weight, and means carried by said float for releasing said shoes when said float reaches a given level.
- 50 55 2. A flow control device comprising a frame adapted to be removably mounted in a vessel to be filled, a float guided in said frame, a supply pipe adapted for insertion in said vessel through said frame, a valve in said pipe, a weight normally tending to close said valve, a cable adapted to lift said weight and open said valve, gripping shoes adapted to hold said cable against the action of said weight, arms extending upwardly from said float, and a member carried by said arms and adapted to release said shoes when said float reaches a given level.
- 60 65 3. A flow control device comprising a frame adapted to be removably mounted in a vessel to be filled, a float guided in said frame, a supply pipe, adapted for insertion in said vessel through said frame, a valve in said pipe, a weight normally tending to close said valve, a cable adapted to lift said weight and open said valve, pivoted levers carrying gripping shoes adapted to hold said cable against the action of said weight, adjustable arms extending upwardly from said float, and a member carried by said arms and adapted to engage said levers to release said shoes from said cable when said float reaches a given level.

70 lift said weight and open said valve, gripping shoes adapted to hold said cable against the action of said weight, adjustable arms extending upwardly from said float, and a member carried by said arms and adapted to release said shoes when said float reaches a given level.

4. A flow control device comprising a frame adapted to be removably mounted in a vessel to be filled, a float guided in said frame, a supply pipe adapted for insertion in said vessel through said frame, a valve in said pipe, a weight normally tending to close said valve, a cable adapted to lift said weight and open said valve, gripping shoes adapted to hold said cable against the action of said weight, means carried by said float for 10 releasing said shoes when said float reaches a given level, and a tensioned pulley adapted to wind said cable.

5. A flow control device comprising a frame adapted to be removably mounted in a vessel to be filled, a float guided in said frame, a supply pipe adapted for insertion in said vessel through said frame, a valve in said pipe, a weight normally tending to close said valve, a cable adapted to lift said weight and open said valve, pivoted levers carrying gripping shoes adapted to hold said cable against the action of said weight, and means carried by said float for 15 engaging said levers and releasing said shoes from said cable when said float reaches a given level.

6. A flow control device comprising a frame adapted to be removably mounted in a vessel to be filled, a float guided in said frame, a supply pipe adapted for insertion in said vessel through said frame, a valve in said pipe, a weight normally 20 tending to close said valve, a cable adapted to lift said weight and open said valve, pivoted levers carrying gripping shoes adapted to hold said cable against the action of said weight, means carried by said float for 25 engaging said levers and releasing said shoes from said cable when said float reaches a given level.

7. A flow control device comprising a frame adapted to be removably mounted in a vessel to be filled, a float guided in said frame, a supply pipe adapted for insertion in said vessel through said frame, a valve in said pipe, a weight normally 30 tending to close said valve, a cable adapted to lift said weight and open said valve, pivoted levers carrying gripping shoes adapted to hold said cable against the action of said weight, means carried by said float for 35 engaging said levers and releasing said shoes from said cable when said float reaches a given level.

8. A flow control device comprising a frame adapted to be removably mounted in a vessel to be filled, a float guided in said frame, a supply pipe adapted for insertion in said vessel through said frame, a valve in said pipe, a weight normally tending to close said valve, a cable adapted to lift said weight and open said valve, pivoted 40 levers carrying gripping shoes adapted to hold said cable against the action of said weight, adjustable arms extending upwardly from said float, and a member carried by said arms and adapted to engage said levers to release said shoes from 45 said cable when said float reaches a given level.

ALBERT KINGSLEY.
